UNITED STATES PATENT OFFICE.

ROBERT ARNOLD TARR, OF BEDMINSTER, ENGLAND, ASSIGNOR TO LESLIE DUNN, OF BRISTOL, ENGLAND.

GRATE FOR STEAM-GENERATOR FURNACES.

No. 927,295.

Specification of Letters Patent.

Patented July 6, 1909.

Application filed December 31, 1907. Serial No. 408,854

To all whom it may concern:

Be it known that I, ROBERT ARNOLD TARR, a subject of the King of Great Britain and Ireland, residing at Melville Terrace, Bedminster, England, have invented an Improved Grate for Steam-Generator Furnaces, of which the following is a specification.

The special feature of the invention is that 10 the grate is composed of rocking bars or sections which turn the fuel over several times during its passage through the furnace. The fuel is thus broken up and a light open fire is produced, whereby practically 15 perfect combustion is obtained. The stoker thus accomplishes all that can be effected by the best hand stoking by the constant use of the slicing bar.

The details of construction, arrangement, 20 and operation of parts are as hereinafter described, and illustrated in the accompanying drawing, in which—

Figure 1 is a vertical longitudinal section of a furnace grate constructed according to 25 my invention. Fig. 2 is a perspective view of one of the rocking grate sections, or fire-bars. Fig. 3 is a plan view of a fire-bar, or grate section. Fig. 4 is a rear elevation of the same. Fig. 5 is a plan of a portion of 30 the endless chain employed for rocking or tilting the fire-bars, or grate sections. Fig. 6 is a front elevation of a boiler fitted with this apparatus.

The apparatus comprises fixed bars and 35 rocking bars, the latter being arranged between the former and approximately sector-shape in transverse section. The movable fire-bars are journaled eccentrically at each end in a frame and adapted to rock or tilt in 40 a vertical plane, when actuated by means adapted for the purpose, which in this case consist of endless chains *d*. The vertical pendent portions of the fire-bars *a* are provided with open slots, or notches, at *b* as 45 shown in Fig. 2, to receive one or more such chains *d*, which run on pulleys *e*, *f*, and are driven by gearing actuated by any suitable motor. The pulleys *e* are arranged at the 50 ends of the grate. The chains *d* travel continuously and are each provided with laterally projecting pins *c*. Thus, as the chains travel through the notches or open slots *b* of the fire-bars, or grate sections *a*, the latter are rocked, or thrown upward, successively, as shown by dotted lines in Fig. 1.

When thus tilted, they discharge their load of fuel from one fire-bar or grate section on to the one in rear of it, and in this way the fuel is advanced from the front of the furnace to the rear end of the same. When the 60 tilting pins *c* have passed through the slots *b* in one fire-bar, or grate section, the latter being weighted on one side returns to its normal position by gravity, and the next bar in succession is then similarly operated. 65 The return of the fire-bars to normal position by gravity is due to the fact that they are pivoted eccentrically, being thus weighted on one side, as shown. Their top portions are flat, and also horizontal when the 70 fire-bars are in their normal position. The continuous travel of the upper runs of the chains *d* thus rocks all the fire-bars successively, from rear to front, and each fire-bar in turn discharges from front to rear the incandescent fuel resting thereon. Such successive tilting of the fire-bars will obviously go on so long as the chains are caused to travel.

Beneath the upper lap or run of each of the 80 chains *d*, and between the slots *b*, a bar *h* of angle iron or the like is arranged lengthwise of the combustion chamber and supported by cross bars *i*, and serve to limit the sagging of the chains.

A fuel feeder *g* is arranged beneath the hopper and is worked by mechanism *l* in the usual manner.

I provide a steam distributor which is 90 located at the rear of the fire-grate and consists of a cast-iron box *m* having a perforated face *n* through the perforations or apertures *o* of which the steam passing from the pipe *p* is discharged into the accumulated coke which is heated between the said distributor 95 and the front of the bridge.

q is a feed pipe for pipe *p*.

A pipe *r* (Fig. 1) is preferably provided within the steam pipe for supplying volatile 100 hydrocarbon to the coke.

What I claim is:

1. In a furnace, the combination with a frame and a series of rocking fire-bars arranged side by side transversely of said frame, and journaled eccentrically so they are weighted on one side, of an endless traveling chain arranged beneath said bars and having portions which, while the upper run of the chain travels from rear to front of the grate, come in contact with, and then re- 110

leases, the lower portion of said fire-bars, whereby they are successively rocked from rear to front of the furnace, and then restored to the normal position by gravity, as described.

2. In a furnace, the combination with a supporting frame and a series of fire-bars arranged transversely to the direction of travel of the fuel and journaled eccentrically and 10 having pendent portions provided with slots, of endless traveling chains arranged below and parallel to the grate whose upper run travels from rear to front of the grate and is arranged in the said slots and pro-

vided with projections adapted for contact 15 with portions adjacent to the slots, whereby the fire bars are successively rocked from rear to front of the furnace, and the fuel resting thereon thrown in the opposite direction as shown and described.

20 In testimony whereof I have hereunto signed my name to this specification in the presence of two subscribing witnesses.

ROBERT ARNOLD TARR.
